UNITED STATES PATENT OFFICE.

FREDERICK C. BLANCHARD, OF DETROIT, MICHIGAN, ASSIGNOR TO DETROIT LUBRICATOR COMPANY, OF DETROIT, MICHIGAN, A CORPORATION OF MICHIGAN.

VALVE.

1,427,256.

Specification of Letters Patent. Patented Aug. 29, 1922.

Application filed October 25, 1920. Serial No. 419,216.

To all whom it may concern:

Be it known that I, FREDERICK C. BLANCHARD, a citizen of the United States of America, residing at Detroit, in the county of Wayne and State of Michigan, have invented certain new and useful Improvements in Valves, of which the following is a specification, reference being had therein to the accompanying drawings.

10 The invention relates to valves designed for installations in which there is only an occasional operation, and it is the object of the invention to obtain a construction that is always operative either from closed or 15 open position. To this end the invention consists in the construction as hereinafter set forth.

In the drawings:

Figure 1 is a central longitudinal section 20 through the valve;

Figure 2 is a cross-section on line 2—2 of Figure 1;

Figure 3 is a similar section on line 3—3 of Figure 1.

25 Where valves remain dormant for long periods of time, there is danger that they will become inoperative, due either to the corrosion and adhesion of contacting surfaces, or the lodgment of sediment, which prevents 30 perfect seating. There is also danger of leakage through the packing material for the stem where the latter is operated after a long period of inaction. With my improvement these defects are avoided by a 35 simple construction, as follows:

A is the valve casing which as shown is in the form of a cross having a bore B extending completely through one pair of aligned arms and transverse bores C and D 40 extending through the other pair of arms, but not intersecting each other or the first-mentioned bore. E and F are bores extending at right angles from the bores C and D and arranged parallel with the bore B. G

45 is a cap having a threaded engagement with the end of the casing to which the bores B, E and F extend, said cap forming a chamber for receiving a disk valve H mounted on a stem I passing through the bore B.

50 J is an enlarged or counterbored portion of the bore B, in which is arranged a packing gland formed of the member K sleeved upon the stem, the packing material L and a spring M which is arranged between the 55 member K, and a collar N secured to the

stem. The collar forms a closure for the upper end of the counterbore and the reaction of the spring will exert pressure on the packing and also draw the disk H towards a seat on the casing.

60 The disk H is provided with one or more apertures O for registration with one or both of the bores E and F and to prevent adhesion between the disk and the seating surface, the latter is restricted in area. 65 Thus as shown in Figure 2, a boss P surrounding the bore F forms a seat for the valve and to hold the disk from tilting, bosses Q and R are arranged at angularly spaced intervals. The total area of bearing 70 surface is relatively small, and consequently, there is no danger of adhesion between the valve and its seat which cannot be easily broken by the turning of the stem.

75 With the construction as described, in use, the valve is connected with the passage C communicating with the inlet conduit and the passage D with the outlet. Thus the fluid pressure in the inlet will act in conjunction with the spring M to hold the valve 80 disk to its seat, but this pressure is not sufficient to interfere with the operation of the valve. The passage E preferably communicates with the chamber containing the valve 85 intermediate the bearing points for the valve being thus in constant communication with said chamber regardless of the position of the valve. Thus the valve may remain stationary for any length of time and whenever there is occasion to use it either for 90 shutting off or turning on the fluid, this may be successfully accomplished. In case of the deposit of sediment upon the disk, the clearance between the disk and the casing intermediate the bearing plugs or bosses will prevent 95 said sediment from finding access to the seat.

The packing material L is preferably of an indestructible and non-corrosive nature, such, for instance, as a mixture of stranded 100 lead and graphite. The pressure of the spring J being constantly exerted on the packing, it will maintain a leak-proof joint at all times.

105 What I claim as my invention is:

1. A valve comprising a casing having inlet and outlet passages communicating with a common chamber, a rotary disk having an aperture for registration with one of said passages, a seat for said disk comprising an 110

annular portion surrounding the passage controlled thereby, and angularly spaced bearings for holding the disk in the plane of said seat, a stem for revolving said disk passing out from said casing, and means for resiliently holding said disk to its seat.

2. A valve comprising a casing of cross form, having inlet and outlet passages in opposite arms thereof communicating with a common chamber in the stem of the cross, a rotary disk in said chamber having an aperture for registration with one of said passages, a shaft for rotating said disk passing through the stem of the cross, a seat for the disk including an annular portion surrounding the passage controlled thereby, and angularly spaced portions for holding the disk in a fixed plane of rotation, a packing gland for said shaft, and a spring upon said shaft reacting to resiliently press upon said packing gland and to hold said disk to its seat.

3. A valve comprising a cross-shaped casing having inlet and outlet passages in opposite arms thereof, respectively communicating with passages extending through the stem portion of the cross, a hollow cap for said stem portion forming a chamber with which said passages communicate, a rotary disk valve in said chamber having an aperture for registration with one of said passages, a seat for said disk valve comprising a raised portion, means in spaced relation to said seat for determining the plane of rotation of said disk, a shaft for rotating said disk passing through the stem portion of the cross outside of said casing, a packing gland in the counterbore surrounding said shaft, a

collar on said shaft also engaging said counterbore, and a spring sleeved on said shaft reacting upon said collar and packing gland to resiliently press upon the packing and hold said disk to its seat.

4. A valve comprising a cross-shaped casting having inlet and outlet passages in the opposite arms thereof, and respectively communicating with downwardly extending passages in the stem portion of the cross, a hollow cap for the lower end of the cross forming a chamber with which said passages communicate, a rotary disk in said chamber having a port for registration with one of said passages, a shaft for said disk passing out through the stem portion of the cross, a seat for said disk including an annular portion surrounding the passage controlled thereby, an angularly spaced bearings for holding the disk in a fixed plane, a packing gland in a counterbore in said casing surrounding said shaft, a collar on said shaft for closing the outer end of said counterbore, and a spring sleeved on the shaft intermediate said collar and packing gland.

5. A valve comprising a casing having inlet and outlet passages communicating with a common chamber, a rotary disk in said chamber having a port for registration with one of said passages, a raised seat for said disk limited in area to a relatively small portion of the disk surface, means for holding said disk in the plane of the seat, and a stem for rotating said disk passing outward from the casing.

In testimony whereof I affix my signature.
FREDERICK C. BLANCHARD.
